UNITED STATES PATENT OFFICE

JOHN WILLIAM KELLY, OF LONG BEACH, CALIFORNIA

MUSICAL NOVELTY

Application filed December 23, 1930. Serial No. 504,234.

This invention relates to a musical novelty which may be used in the playing of syncopation music, but is also useful as a means of instructing children in that it is easy to play and a child can readily learn to play music thereon.

An object of my invention is to provide a musical instrument which is simple in construction and inexpensive to manufacture.

Another object is to provide a musical novelty of the character stated which can be readily played by an amateur with comparatively little instruction or practice.

Other objects, advantages, and features of invention may appear from the accompanying drawings, the subjoined detailed description, and the appended claims.

In the drawings

Figure 1 is a side elevation of my musical novelty.

Figure 2 is a view looking from the right of Figure 1.

Figure 3 is a fragmentary view looking from the left of Figure 1.

Figure 4 is a top plan view.

Referring more particularly to the drawings, the numeral 1 indicates a cone preferably formed of paper and in one continuous piece. The overlapping edges are held together by means of a flap 2 which is cut from one end, said flap extending under a strip 3 which is cut from the other end. A flap 4 extends over the edge to further hold the cone in position at the bottom. The bottom of the cone is open, and the top is covered by a rubber mouthpiece 5 which is stretched taut in a manner to be further described.

One end of the rubber piece 5 is held stationary by a suitable means such as a rivet or pin 6. The other end of the piece is bifurcated to form the two strips 7-8. The strips 7-8 extend under flaps 9-10 which are cut in the cone 1. The purpose of the flaps 9-10 is to hold the strips 7-8 against retraction after said strips have been pulled down to stretch the mouthpiece 5 tightly across the top of the cone. The mouthpiece is further held in proper position and at proper tension by means of a ring 11 which encircles the cone adjacent the top thereof.

The flat stretched part of the mouthpiece 5 has a hole or opening 12 therein through which air is blown to provide a musical note. One side of the mouthpiece 5 is gathered under the ring 11, but the other side is left 55 free so that it will vibrate properly.

Having described my invention, I claim:

1. A musical novelty comprising a cone, a rubber mouth-piece stretched across one end of the cone, means fixedly securing one end of 60 said mouthpiece to the cone, strips on the other end of the mouthpiece, stay-flaps formed on the cone, said strips extending under the stay-flaps whereby the tension of the mouthpiece across the cone is adjusted. 65

2. A musical novelty comprising a cone, a rubber mouthpiece stretched across one end of the cone, means fixedly securing one end of said mouthpiece to the cone, strips on the other end of the mouthpiece, stay-flaps 70 formed on the cone, said strips extending under the stay-flaps whereby the tension of the mouthpiece across the cone is adjusted, and a ring encircling the cone adjacent the top thereof, said ring engaging the mouth- 75 piece.

3. A musical novelty comprising a paper cone, a rubber mouthpiece extending over one end of the cone, said mouthpiece having an opening therein, a pin extending through 80 the cone and fixedly holding one end of the mouthpiece, a pair of flaps cut from the cone, the other end of said mouthpiece being bifurcated, said bifurcated end passing under said flaps, a ring encircling the cone adjacent 85 the top thereof, said ring engaging the mouthpiece and means securing the edges of the paper cone together.

In testimony whereof, I affix my signature.

JOHN WILLIAM KELLY. 90
